VACUUM CLEANER SWITCH

Ferman C. Doughman, Stamford, Conn., assignor
to Electrolux Corporation, Dover, Del., a corpora-
tion of Delaware

Application August 27, 1938, Serial No. 227,030

6 Claims. (Cl. 200—52)

My invention relates to vacuum cleaners and more particularly to vacuum cleaners of the, so-called, inside bag type having a switch adapted for operation by the application of foot pressure.

5 Portable appliances in general receive relatively hard usage and this is particularly true of vacuum cleaners. A switch for a vacuum cleaner which may be operated by foot pressure is of a considerable convenience. However, such 10 a switch must be able to withstand forces very greatly in excess of any force necessary for the operation of the switch.

An object of my invention is to provide a switch mounting which will withstand these excessive forces.

Another object of my invention is to provide a switch mounting which facilitates assembly of the switch and is of easy access for removal or replacement.

20 A further object of my invention is to provide a switch mounting which will not become loosened in the operation of the vacuum cleaner.

What I consider to be novel and my invention may be better understood by reference to 25 the following specification and appended claims when considered in connection with the accompanying drawing, in which

Fig. 1 is a side elevation of a vacuum cleaner broken away in part;

30 Fig. 2 is an enlarged detail view of the switch and associated parts;

Fig. 3 is a sectional view taken along the line 3—3 of Fig. 2;

Fig. 4 is a sectional view taken along line 4—4 35 of Fig. 3;

Fig. 5 is a sectional view taken along line 5—5 of Fig. 3; and

Fig. 6 is a perspective view of a channel member.

40 Referring to the drawing, 10 indicates a vacuum cleaner unit of the inside bag type. A flexible hose 11 is connected to vacuum cleaner unit 10 at one end and to a cleaning tool 12 through a tube 13 at the other end. Cleaning tool 12 may 45 be connected directly to the flexible hose 11 if desired. A motor fan unit 14 produces a flow of air through the cleaner unit 10 from left to right as shown in Fig. 1. Air drawn in through the cleaning tool 12 carries with it dirt and dust

50 on the surface being cleaned. The dust and dirt are separated from the air in its passage through the cleaning unit 10 by a dust bag 15.

The operation of the motor fan unit is controlled by an electric switch 16 mounted in a rear end housing 17. Switch 16 is of the type

designed for operation by the application of foot pressure on a button 18. While the switch 16 and housing 17 may be designed to withstand the greatest force that may be applied to the button 18 for operation of the switch 16, there 5 is a tendency for the securing means holding the switch 16 in the housing 17 to be loosened by this repeated application of excessive force. Any part of the switch mounting which is loosened may fall in the motor chamber and damage the 10 motor. The securing means of this invention is so designed to eliminate any possibility of the loosening of the parts securing the switch 16 in housing 17.

Switch 16 is provided with two side projections 19 (Fig. 5) which overlie inwardly extending shoulders 20 of housing 17 located at the sides of the opening 21 through which the switch 16 extends. A switch cover 22 covers the top of switch 16 and has an opening 23 through 20 which button 18 projects. Cover 22 is provided with inwardly turned flanges 24 (Fig. 4) which rest on shoulders 20.

A U-shaped hairpin spring 25 has two arms 26 of undulated shape which extend between the 25 projections 19 of switch 16 and the flanges 24 of cover 22. The tops of the undulations of the arms 26 engage the projections 19 and the bottoms engage the flanges 24. The arms 26 hold the top of the switch 16 in engagement with 30 the top of the cover 22. The ends of the arms 26 extend into two channel members 27 provided with wings 28. Channel members 27 are positioned over the shoulders 20 of housing 17. The wings 28 extend inwardly as shown in Fig. 2 to 35 provide a larger area of contact with the housing 17. Pin 29 extends through an aperture 30 in housing 17 and engages the back of the hairpin spring 25 securing it to the housing 17, as shown in Fig. 4. An enlarged head 31 of pin 40 29 abuts a ring 32 to which the housing 17 is secured. This prevents the pin from falling out after the housing 17 is secured to the ring 32. The channel members 27 prevent the rocking of the switch 16 and are held in position between 45 the housing 17 and the switch 16. The undulated arms 26 give some resiliency to the switch 16 without permitting excessive movement of the switch.

In the assembly of the switch 16 and the 50 housing 17, the cover 22 is first inserted over switch 16. The channel members 27 are inserted over the shoulders 20 in opening 21. The spring 25 is then inserted in position with the arms 26 extending between the projections 19

and the flanges 24. The switch 16 is inserted in the opening 21 and the spring 25 forced home with the ends of its arms 26 entering channel members 27. Pin 29 is inserted in aperture 30 5 into engagement with spring 25. The assembly of the switch 16 and housing 17 is then secured to the ring 32. Access to the switch 16 for removal or replacement can be obtained only by removing the housing 17 from the ring 32. The 10 switch 16 may then be removed by removing the parts in the reverse order of the assembly of the switch in the housing as described above. No part of the switch mounting can become loosened as long as the housing 17 is secured to the ring 15 32.

What I claim is:

1. In a vacuum cleaner, a switch housing having an opening and shoulders located around the opening, a switch extending into the opening in 20 the housing and having side projections overlying the shoulders around the opening, a switch cover having inturned flanges resting on the shoulders around the opening, a spring extending between the side projections of the switch and 25 the flanges of the cover, and means cooperating with the spring for locking the switch to the housing.

2. In a vacuum cleaner, a housing having an opening, a switch extending into said opening having side projections overlying the edges of the opening, a cover for said switch having inturned flanges resting around the edges of the opening of said housing, a hairpin spring having arms extending between the side projections of said switch and the flanges of said cover to lock said switch and cover together, means securing the free ends of the spring to the housing, and a pin extending through an aperture in said housing and engaging said spring to secure said switch 40 and cover to said housing.

3. A vacuum cleaner including a housing having an opening, a switch adapted for operation by foot pressure extending into said opening and having side projections overlying the edges of said opening, a cover for said switch having inturned flanges resting on the edges around said opening, a U-shaped member having arms ex-

tending between the side projections of said switch and the inturned flanges of said cover, channel members located between the switch and housing and receiving the free ends of the arms of said member, and a pin extending through an aperture in said housing engaging said member to secure the member to the housing.

4. In combination with a vacuum cleaner having a casing and an end ring secured to the casing, a housing secured to the end ring and having an opening, a switch extending into the opening in the housing and having projections overlying the edges of the opening, a switch cover having inturned flanges resting around the 15 edges of the opening, a member extending between the side projections of the switch and the flanges of the cover, means securing one end of said member to said housing, and a headed pin abutting the end ring and extending through an 20 aperture in the housing to lock said member to the housing.

5. In combination with a vacuum cleaner having a casing, a housing secured to the casing having an opening, a switch extending in the 25 opening in the housing having side projections overlying the edges of the opening, a switch cover resting on the edges around the opening of the housing, a hairpin spring extending between the switch, side projections and cover to 30 secure them together, means securing one end of the spring to the housing, and a headed pin abutting the casing extending into an aperture in the housing and engaging the spring to lock the switch and cover to the housing.

6. In a vacuum cleaner having an opening and inwardly extending shoulders located around the opening, a switch extending into the opening and having side projections overlying the shoulders around the opening, a cover having 40 inturned flanges resting around the edges of the opening, and a spring having arms of undulated shape extending between the side projections of the switch and the flanges of the cover, and means securing the spring to the housing.

FERMAN C. DOUGHMAN.
